UNITED STATES PATENT OFFICE.

HEINRICH GRAU, OF CASSEL, PRUSSIA, GERMANY.

ELECTRO-MAGNETIC MOTOR FOR CLOCKS.

SPECIFICATION forming part of Letters Patent No. 279,239, dated June 12, 1883.

Application filed August 25, 1882. (No model.) Patented in Germany May 5, 1882, No. 18,057.

To all whom it may concern:

Be it known that I, HEINRICH GRAU, a subject of the King of Prussia, residing at Cassel, Prussia, German Empire, have invented certain new and useful Improvements in Electro-Magnetic Motors; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

The invention consists in certain improvements in the construction of electro-magnetic indicating devices with rotating polarized armature, substantially as hereinafter fully described, and specifically pointed out in the claims.

In the accompanying drawings, Figures 1 and 2 are rear and side elevations, respectively, of the improved indicating devices; and Fig. 3 shows the armature and its steel magnet in elevation. Figs. 4 and 5 are detail views of the armature, and Fig. 6 is a detail view of the stop mechanism on an enlarged scale.

Like letters of reference indicate like parts in the above figures of drawings.

The mechanism is supported by a suitable frame-work, F, in which a shaft, S', of brass, has its bearings, as shown at d and e. The said shaft passes loosely through the legs of a strong steel magnet, M, and carries between the poles a and b of the magnet the armature A A', that serves to rotate said shaft, which latter communicates its movements, through the medium of a pinion, p', to a gear-wheel, m, the prolonged end of the shaft of which carries the minute-hand.

The armature is composed of two sections, A A', each having two arms, f h and g i, respectively, formed on opposite sides of a central hub or bearing, and of such construction that, when the sections are rigidly secured to the brass sleeve e in a position so that the arms of one will lie between the arms of the other, the two sections will form a toothed wheel capable of operation like an escapement or ratchet wheel, as shown in Fig. 3.

Owing to the proximity of the hubs of the armature-sections to the poles of the magnet M, said sections are magnetized, and are of the

same polarity as that of the adjacent poles of said magnet M—that is to say, the arms f h of the section A will be the N. poles, and the arms g i of the section A' the S. poles, and the said poles will alternate with one another.

The armature is arranged in proximity to and partly between the coils C C' of an electro-magnet, M', the poles k and l of which have their left sides beveled off, so as not to interfere with the free rotation of the armature. The tendency of the latter relatively to the poles of the magnet M' is to assume a position of rest, in which position, owing to the peripheral form of said armature, its arms will always lie in closest proximity to the poles of the electro-magnet. If an electric current is sent through the magnet M', so that k will be the N. pole and l the S. pole, then k and f will be of like polarity and l and g will be of like polarity. The result of this electric relation between the electro-magnet and the armature will be that k and l will repulse f and g, respectively, and attract g and h, respectively, thereby imparting to the armature a quarter of a revolution. The armature will then assume a position of rest, for the reason that the arms g and h of the armature-sections now in proximity to the poles k and l of the magnet are of unlike polarity. If, however, the electric current is reversed, l will become the N. pole and k the S. pole of the electro-magnet, and the polarities of l h and k g, respectively, will again be alike, whereby the said sections are again repulsed, and the sections h and i attracted to impart a quarter of a revolution to the shaft S', and through it to the minute-hand, and so on.

In order to operate the mechanism, it is therefore necessary to send a current of electricity through the electro-magnet at fixed periods or intervals, reversing the current each time, as will be readily understood. To prevent a retrograde movement of the minute-hand, and to prevent the armature from moving beyond its position of rest by a too rapid succession of the electric currents, I employ a stop mechanism constructed and operating as follows, referring more particularly to Fig. 6.

Upon the shaft S' is mounted a disk, D, in which is formed a ratchet-shaped guide-groove, d, whose inner edge forms a ratchet the teeth of which are formed by the curve or cam surfaces q and the radial shoulders or surfaces r.

The outer edge of the groove forms also a ratchet having curved or cam surfaces *n*, inclined surfaces *s*, and the radial faces or shoulders *t*. In this groove rides a semicircular pin, 5 *o*, attached to one end of a weighted lever, *p*, pivoted at *S'* upon the supporting-frame, the flat face of the pin lying normally against the radial face *r* of one of the teeth forming the inner edge of the groove, held there by the 10 weighted lever *p*. When the shaft *S'* is rotated by the armature, the cam-face *q* depresses the pin *o*, and, owing to the rapid motion of the armature before the lever can lift the pin over the point of the tooth, said pin strikes 15 the incline *s* of the outer edge of the groove, on which it rides until it comes in contact with the radial face or shoulder *t*, and instantaneously stops the movement of the shaft and armature. Should the pin *o* recoil on striking 20 the shoulder *t*, it will then be in a position to come in contact with the radial face or shoulder *r* of the inner edge of the groove, which also prevents a retrograde movement of the disk. After the movement of the shaft has been arrested, as described, the pin will be lifted by 25 the lever into its normal position.

The characteristic advantages of this mechanism are the following: It may be operated by a comparatively weak electric current. 30 The mechanical power generated is directly proportional to the power exerted during every moment of motion. In starting, when the inertia of the operating mechanism has to be overcome, the power is greatest, because at 35 that moment there is not only an attracting but simultaneously a repulsing power in the direction of motion exerted upon the said mechanism. The armature, in proportion to its dimensions, is highly magnetic, and this 40 magnetism may be increased by a corresponding increase of the power of the steel magnet. By the reversal of the current the formation of remanent magnetism in the electro-magnet, as well as the influence of atmospheric electrical disturbances, are avoided.

Having now described my invention, what I claim is—

1. In an electro-magnetic motor, the combination, with an electro-magnet, of a permanent magnet and an armature polarized thereby, composed of two bars isolated from each other, the ends of which intermatch, as described, forming alternating positive and negative poles, said armature being arranged relatively to the electro-magnet, as described, substantially as and for the purposes set forth. 55

2. In an electro-magnetic-motor mechanism, the combination, with an electro-magnet, and a polarized rotating armature having positive and negative poles alternating with each other, and arranged relatively to the said magnet, as described, of appliances to limit the movements of the armature in one direction at each pulsation of the electric current, as set forth. 60 65

3. In an electro-magnetic-motor mechanism, the combination, with an electro-magnet, and a polarized rotating armature having alternating positive and negative poles *f g h i*, and arranged relatively to the electro-magnet, 70 as set forth, of appliances to simultaneously limit the movement of the armature in both directions, substantially as and for the purposes specified.

4. In an electro-magnetic-motor mechanism, the combination, with an electro-magnet and a steel magnet, of an armature composed of two sections, *A* and *A'*, and arranged relatively to said magnets, as described, whereby the sections of the armature are magnetized 80 and the force of the electric current passing through the electro-magnet is increased, substantially as and for the purposes specified. 75

5. The combination, with the electro-magnet *M'*, of the armature composed of the sections *A* and *A'*, sleeve *e*, shaft *S'*, and the magnet *M*, arranged for co-operation as described. 85

6. In an electro-magnetic-motor mechanism, the combination of an electro-magnet and a train of gearing for operating indicating devices, a polarized rotating armature, *A*, for operating said train of gearing, a magnet for magnetizing the armature, and mechanism to limit the movement of the armature in either 95 direction at each pulsation of the electric current, substantially as and for the purposes specified. 90

7. An armature for electro-magnets, constructed of two sections, *A* and *A'*, isolated 100 from each other, and forming together an escapement or ratchet wheel, whereby said sections may be polarized and the teeth of the armature form a series of alternate + and - poles, as and for the purposes specified. 105

In testimony whereof I affix my signature in presence of two witnesses.

HEINRICH GRAU.
